[57] ABSTRACT

A current limiting fuse holder and method of making

the same in which the metal fittings at each end of the fuse holder are secured to the glass resin impregnated filament wound tube or housing of the fuse holder by internal teeth. The fittings may be of the split type so that each half of the fitting may be compressed into the filaments before the latter are cured and have tapered teeth on the inside of a construction so that the teeth closest to the outer end are the longest and then decrease in length toward the inner end of the fitting so that the teeth penetrate and lock into different layers of the winding forming the housing. Under another embodiment, grooves may be machined into a cured filament wound tube and an annular fitting of different length teeth are threaded into the grooves. In both these cases, the fittings and the inner layers of the filaments of the tube or housing are overwound with glass resin impregnated filaments to lock the fittings in place and complete the housing and fuse tube after which the entire assembly is cured. In another embodiment of the invention, the split fitting is not overwrapped with the filaments but rather the fitting is externally threaded to receive a sleeve which is threaded onto the fitting after curing of the assembly or the fitting may be otherwise clamped to support the fitting in service.

CURRENT LIMITING DEVICE

BACKGROUND OF THE INVENTION

The present invention relates to a current limiting device having a unique fitting assembly and which is designed to withstand extremely high voltages without failure as compared to present devices which are not capable of withstanding the voltage levels obtained by the present invention.

SUMMARY OF THE INVENTION

The invention is directed to a current limiting device and method of making the same for use in holding a fuse which, in service, may be subjected to surges of high voltages.

The fuse holder of the invention consists of a housing formed by layers of continuously wound glass fibers impregnated with a thermosetting resin. At each end of the housing there is located a metal fitting either of the split-ring type or of solid ring-type construction. Each fitting has internal tapered teeth and the teeth are of varying length.

The longest tooth is located at the outer end of each fitting and the teeth gradually decrease in length so that the shortest tooth is located at the inner end of each fitting. The teeth of the fitting thus penetrate into different layers of the winding of the housing and this effects transfer of the applied tensile load the metal fittings will be subjected to in service uniformly throughout the wall of the housing or fuse holder tube. The fittings are overwound with layers of resin impregnated glass filaments to lock the fittings securely to the housing, and the entire unit is cured.

Under one method of the invention, the resin impregnated continuous glass fibers are wound back and forth about a mandrel to provide a housing or tube of a plurality of layers of filaments. The winding is then interrupted and split ring fittings are applied over the uncured housing. The fittings internally have tapered teeth and the teeth are of different length, the longest tooth being on the outer end of the fitting and the teeth gradually decrease in length to the shortest at the inner end of the fitting. The split ring fittings are compressed together into the uncured housing. The housing and fitting are returned to the winding machine and the fittings are overwrapped with resin impregnated glass filaments to lock the fittings to the housing. Thereafter the fuse holder is finally cured and removed from the mandrel.

Under another embodiment of the invention after the housing is initially formed, it is cured on the mandrel and then removed and grooves of helical form and of inwardly decreasing depth are machined in the ends of the housing. Metal solid ring-like fittings having tapered teeth or threads of different depth corresponding to the grooves are threaded into the grooves at the ends of the housing. Thereafter the fuse holder is placed on a mandrel and the fittings are overwrapped with thermosetting resin impregnated glass filaments and the windings are cured and the completed fuse holder or current limiting device is removed from the mandrel.

Under another embodiment of the invention, the split fittings are not overwound with the resin impregnated filaments but instead the fittings are externally threaded and a sleeve is threaded onto each fitting to support the fitting in service.

Under all the described embodiments the tube or housing is formed on a mandrel of a considerable length so that a plurality of fuse holders can be severed from a single elongated tube.

DESCRIPTION OF THE DRAWINGS

In the drawings:

FIG. 1 is a longitudinal section with parts in elevation illustrating a plurality of layers of filaments wound on a mandrel to provide the housing of the fuse holder;

FIG. 2 is a longitudinal section of the fuse holder of the invention with parts in elevational and without any fuse in place but with the terminal fittings applied and overwrapped;

FIG. 3 is an enlarged longitudinal section of a fitting end of a fuse holder illustrating the difference in the depth or length of the teeth of the terminal fitting and their penetration of the filament layers and the overwrapping thereof;

FIG. 4 is a cross section taken on line 4-4 of FIG. 3 to illustrate the split ring construction of the fitting;

FIG. 5 is a sectional view with parts in elevation illustrating the compressing of the split ring terminal fittings into the end of a fuse holder housing;

FIG. 6 is perspective view illustrating a second embodiment of the invention with grooves machined in the housing;

FIG. 7 is a detailed sectional view illustrating a solid ring-like terminal fitting threaded into the grooves;

FIG. 8 illustrates in elevation a locking ring secured around the fitting to hold it in place.

FIG. 9 is a top plan view of the locking ring before assembly with the fitting of FIG. 8;

FIG. 10 is a side elevational view of a fuse holder with parts in section illustrating another embodiment of the invention.

FIG. 11 is a side elevational view with parts in section and illustrating a split ring terminal fitting threaded throughout, and which has been assembled on the resin impregnated filament wound tube;

FIG. 12 is a side elevation with parts in section illustrating the holding of the split fitting on the tube during curing; and

FIG. 13 is a side elevation with parts in section of the tube and split ring fitting with a locking sleeve threaded onto the fitting to support the fitting in service.

Referring to the drawings, there is shown a fuse holder or current limiting device as illustrated in FIGS. 1-7 having an elongated housing 1 provided by a plurality of layers of continuous glass fibers impregnated with a thermosetting resin applied by the filament winding method. Layers 2, 3, 4 and 5 of the fibers are illustrated in FIG. 3.

The metal terminal fittings 6 are located on the ends of housing 1 and only one fitting will be described as both are the same. The fitting 6 is of the split ring type as illustrated in FIG. 4 and has threads 7 at the outer end for receiving a terminal plug, not shown, and which approach a flange or abutment 8 extending around the body of each half ring of fitting 6.

Internally fitting 6 is provided with the longitudinally spaced and tapered relatively sharp teeth 9. The teeth 9 are shown as equidistant from each other and the outermost tooth 9 is the longest, and the teeth 9 inwardly of outermost tooth 9 decrease in length to the shortest tooth 9 which is the innermost tooth.

The split ring fitting 6 is assembled with layers 2, 3, 4 and 5 of housing 1 when they are uncured by compressing the two halves of the fitting as shown in FIG. 5 into the uncured filament winding layers 2, 3, 4 and 5. Therefore, as illustrated in FIG. 3, the outermost tooth 9 will penetrate into innermost filament layer 2. The next adjacent tooth will penetrate into layer 3 and the next into layer 4, and the innermost tooth 9 will penetrate into outermost filament layer 5. The teeth 9 slant slightly outwardly and preferably extend annularly around each half of the fitting and may be at a slight helix but are not necessarily continuously connected throughout the internal extent of the fitting. By locking the teeth into separate layers of filaments, the effect is to transfer the tensile load on the metal end fittings, which is applied upon fuse interruption, uniformly throughout the wall of housing 1.

The housing 1 of the fuse holder is completed by an overwrap of layers of filament windings 10 wound about the layers 2, 3, 4 and 5 and over the fittings to the thickness desired and up to the abutments or flanges 8 adjacent the threaded ends 7 of the fittings.

In carrying out the method of the invention with respect to the embodiment illustrated in FIGS. 1-4 of the drawing, the first step consists of winding continuous glass fibers impregnated with a thermosetting resin about the mandrel 11 to provide a plurality of layers of filaments such as layers 2, 3, 4 and 5.

This is accomplished by rotating the winding mandrel 11 having a diameter corresponding to the inside diameter of the completed fuse holder in a machine, not shown, capable of dispensing glass roving or fibers impregnated with a thermosetting resin along a predetermined path and under controlled tension. The illustrated layers 2, 3, 4 and 5 are wound at a low angle with respect to the center line of mandrel 11 which will yield maximum tensile values. The housing 1 formed by layers 2-5 is ordinarily made of considerable length so that it can then later be severed into the length desired for each respective fuse holder.

The winding process is then interrupted and before any curing operation, the mandrel 11 and the incomplete housing or tube is removed from the machine and assembled in supporting fixtures 12 so that one portion of the assembled unit rests on the top of half of a split ring fitting, as shown on the right side of the drawing of FIG. 5, which is held by fixtures 12, and another part of the unit rests on additional split rings held by the other fixture 12. Referring only to the fitting assembly shown at the right of FIG. 5, the other half of split ring fitting 6 is then placed over the housing 1 in line with the first half of fitting 6 and the piston 13 of the fixture is lowered by power cylinder 14 to force the internal teeth 9 of the fitting 6 to penetrate the filament layers 2, 3, 4 and 5. The fitting 6 at the left hand side of FIG. 5 is similarly assembled. FIG. 5 shows housing 1 and the mandrel 11 cut off to illustrate the elongation of housing 1 and the severing thereof to provide a number of fuse tubes.

Thereafter, the mandrel 11 with the winding layers 2, 3, 4 and 5 thereon and fittings 6 secured thereto is returned to the winding machine, not shown, and a plurality of layers 10 of continuous glass fiber impregnated with a thermosetting resin are wrapped over layers 2, 3, 4 and 5 at a high angle with respect to the centerline of mandrel 11 and back and forth over metal fittings 6

to lock the fittings 6 into place and to build up layers of fibers to the desired wall thickness. The completed housing 1 is then cured, the mandrel 11 is extracted, and the low angle winding cut off flush with the fitting ends.

FIGS. 6 and 7 illustrate another embodiment of the invention in which a solid annular fitting 15 having internal teeth 16 corresponding to those of fitting 6 in that the outermost tooth 16 is the longest and the teeth gradually decrease in length to the innermost shortest tooth 16. In this embodiment the teeth 16 may be on a slight helix or annular but preferably extend continuously on a helix internally of the fitting.

In this embodiment, the layers of resin impregnated glass filaments wound on the mandrel 11 are cured and the mandrel 11 is extracted therefrom. The grooves 17 are then machined into the ends of fuse holders of a depth corresponding to the varying length of the teeth 16 of fitting 15. Fitting 15 is then threaded onto the end of the cured layers as shown in FIG. 7 to locate the teeth 16 in grooves 17 at varying depths to penetrate the different layers of filaments 2, 3, 4 and 5.

Thereafter the wound filament layers 2, 3, 4 and 5 of housing 1 and the fittings 15 which have been assembled over the ends thereof are assembled on mandrel 11, and a plurality of layers 10 of resin impregnated glass fibers are wrapped over the layers 2, 3, 4 and 5 and fittings 15 the same as described with respect to fittings 6. The assembly is then cured and mandrel 11 extracted to complete the construction of the fuse holder under the method of the second embodiment of the invention.

FIG. 8 illustrates another embodiment of the invention for mechanically holding the fitting during curing. In this embodiment, the split ring fitting 18 there shown as in the first embodiment has teeth 19 which are embedded in the filament wound tube 20 but is provided with horizontally spaced flanges 21. The compressing of the teeth 19 into tube 20 is done when the filaments are in the uncured state such as by the fixture 12, piston 13 and power cylinder 14 illustrated in FIG. 5. However, simultaneously the fixture and piston wrap a locking ring 22 around fitting 18, not shown, between flanges 21 to secure fitting 18 in place. As illustrated locking ring 22 has a tab 23 at one end which in the locking operation is received within the key slot 24 at the other end to effect the locking of ring 22 around fitting 18. The tube 20, which is of considerable length, to receive several fittings and with rings 22 and mandrel 11 in place is then cured. After curing mandrel 11 is removed and fuse holders are formed by severing the tube 20 to the desired lengths and each locking ring 22 is retained and supports split terminal fitting 18 in service.

FIG. 10 illustrates another embodiment of a completed fuse tube assembly which has an inner fuse liner 25 around which is located a layer of hoop windings 26. The hoop windings 26 are encircled by a layer of low angle windings 27. In both cases there are several layers of both types of windings but only one layer of each is illustrated. The split terminal fitting 28 is shown as assembled in place and has the teeth 29 of different lengths which extend into different layers of the windings with the longest tooth being the outermost of the teeth 29 and the shortest tooth 29 being the innermost tooth. The split terminal fitting 28 also has the groove 30 which extends annularly therearound slightly re-

moved from the outer end of fitting 28. An annular end sleeve 31 which in construction is flared outwardly and has an internal flange 32 which is disposed over the end of fitting 28 and sleeve 31 is compressed in assembly to force or crimp flange 32 into groove 30 of fitting 28. The sleeve 31 is threaded internally to receive the desired connection and supports the split fitting 28 in service. As shown a sleeve 31 is also located over the split fitting, not shown, at the other end of the fuse holder, and a molded plastic sleeve 33 is assembled and secured over the body of the fuse holder.

In assembling the fuse tube of FIG. 10, the tube is initially formed on the mandrel 11 by windings 26 and 27. The split fitting 28 is then assembled over the tube and held in place by C-clamp 38 or the like and cured. Thereafter the mandrel 11 is extracted and the tube is cut to length. After the cutting operation the plastic sleeve 33 is assembled over the tube, and the flared end fittings or end sleeve 31 is compressed into place on each end of the fuse tube to support the split fitting 28.

FIG. 11 illustrates a split terminal fitting 34 which has the teeth 35 of different length which penetrate different layers of the filaments in tube 35 and slant slightly outwardly. The filament layers consist of a plurality of internal hoop layers 36 and around which are wound a plurality of layers 37 of filaments at a low angle helix. The fitting 34, however is threaded externally generally throughout its length and as in the first embodiment, the fitting 34 is assembled with the uncured windings of tube 35 by compressing the two halves of the fitting 34 as shown in FIG. 5 so that the teeth 35 penetrate different layers of the uncured windings the same as is illustrated in the previously described embodiments of the invention. The fitting 34 is then clamped in the compressed position such as by C-clamp 38 shown in FIG. 12, and the completed tube and fitting assembly is then cured. The mandrel upon which the tube has been assembled is thereafter extracted and the assembly is cut from the elongated tube 35 to form fuse holder of the proper length as illustrated in the completed fuse holder shown in FIG. 13.

The fuse holder is then completed by threading the annular sleeves 39 onto the split fittings 34 at each end of the fuse holder. The sleeves 39 hold and support fitting 34 in place in service. By employing sleeves 39 as illustrated in this embodiment, this eliminates a second winding operation to secure the fitting in place.

In the method of the last described embodiment the inner hoop layers of the resin impregnated filament wound tube are first formed by winding the filaments on a mandrel such as mandrel 11 shown in FIG. 1. Thereafter, over the hoop layers are wound resin impregnated filaments at a low angle helix. The uncured tube and each split ring terminal fitting 34 with the mandrel is then assembled within a fixture such as that illustrated in FIG. 5 and the teeth of the fitting are compressed into different layers of the filament windings.

The assembly is removed and clamped with C-clamps 38 and cured. Thereafter the mandrel is removed and selected lengths of the tube are severed to form the desired length of each fuse holder. Then the C-clamps 38 are removed and a sleeve 39 is threaded home on each fitting 34 to support the fitting in service.

The fuse holder of the invention and the method of making the same provides a fuse holder in which the metal end terminal fittings are uniquely locked to the filament wound resin impregnated housing by internal teeth penetrating into different layers of the filament windings of the housing of the fuse holder. The fuse holder of the invention stays intact when subjected to high voltage surges and is capable of withstanding high voltage levels.

Various modes of carrying out the invention are contemplated as being within the scope of the following claims particularly pointing out and distinctly claiming the subject matter which is regarded as the invention.

I claim:

1. A current limiting fuse holder, which comprises a tubular housing formed of layers of filament wound fibers impregnated with a thermosetting resin, at least one terminal fitting having internal teeth secured to an end of the housing by the teeth being embedded within different layers of filament wound fibers, and means overlaying the terminal fitting to lock the fitting in place.
2. The current limiting fuse holder of claim 1 in which the terminal fitting is a split ring.
3. The current limiting fuse holder of claim 2, in which the split ring has tapered teeth in that the teeth extending from the outer end of the fitting to the inner end are longest at the outer end and gradually decrease in length to the inner end to engage different layers of the filament windings and are slanted outwardly of the tubular housing.
4. The current limiting fuse holder of claim 1 in which the terminal fitting is of annular solid ring-like construction with internal teeth of varying length, and matching grooves provided in the end of the housing to permit threading of the fitting into the grooves.
5. The current limiting fuse holder of claim 1 in which the means overlaying the terminal fitting are resin impregnated filament windings wound over the terminal fitting.
6. The current limiting fuse holder of claim 1 in which the means overlaying the terminal fitting is a sleeve threaded onto the fitting.
7. The current limiting fuse holder of claim 1 in which the terminal fitting has an external annular groove spaced from the outer end of the fitting, and the means overlaying the fitting is an end sleeve having an annular flange disposed in the groove of the fitting to hold the fitting in place in service.
